UNITED STATES PATENT OFFICE.

MARSHALL M. MODE, OF CAMERON, TEXAS.

COTTON-COMPRESS.

1,038,934.

Specification of Letters Patent. Patented Sept. 17, 1912.

Application filed February 2, 1912. Serial No. 674,891.

To all whom it may concern:

Be it known that I, MARSHALL M. MODE, a citizen of the United States, residing at Cameron, in the county of Milam and State 5 of Texas, have invented new and useful Improvements in Cotton-Compresses, of which the following is a specification.

This invention relates to cotton compresses, and its object is to provide a simple, 10 reliable and efficient construction of compress adapted to be operated by compressed air and embodying a minimum number of parts not liable to bind, cause excess friction or get out of order.

15 The invention consists of the features of construction, combination and arrangement of parts, hereinafter fully described and claimed, reference being had to the accompanying drawings, in which:—

20 Figure 1 is a side elevation of a cotton compress constructed in accordance with my invention. Fig. 2 is a vertical section through the compressor cylinder and contained parts. Fig. 3 is a sectional plan view 25 on line 3—3 of Fig. 2. Figs. 4 and 5 are vertical and horizontal sections on lines 4—4 and 5—5 of Figs. 1 and 2. Fig. 6 is a perspective view of the base. Fig. 7 is a similar view of the plunger guide.

30 In the practical embodiment of my invention, I provide a base board or plate 1 having at one end a pair of branch arms 2 depressed below the plane of the body of the board or plate by offset portions 3. The 35 arms 2 are connected by cross plates 4, forming a base to support a compressor cylinder or chamber 5. This cylinder or chamber consists of a vertical series of rods or belts 6 having lower threaded ends which pass 40 through openings in the arms 2 and cross plate 4 and provided with nuts 7, whereby the parts are clamped together. The rods 6 also have upper threaded ends which pass 45 through a head 8 closing the upper end of said compressor cylinder, and provided with nuts 9 to clamp said head in position.

Arranged within the lower portion of the compressor cylinder is a guide member 10 comprising a cylindrical body having depending diverging legs 11 formed with angularly bent lower ends engaging the bolts 6 between the arms 2 and plates 4, whereby said guide is firmly fastened in position. The body of the guide is formed with an 55 opening 12 in which is slidably mounted a stem 13 carrying at its upper end a com-

pressor block or head 14, between which and the relatively stationary head 8 the cotton or other material is compressed. The stem 13 has a beveled lower end 14' to engage the 60 beveled end 15 of the short arm of an operating lever 16, which is pivotally mounted at a point between its center and the end portion 15 to rock vertically upon an axle pin 17 carried by a pair of bracket lugs 18 65 projecting upwardly from the base board or plate 1 adjacent to the offset portions 3. By this arrangement the base of the compressor cylinder is arranged below the plane of the board or plate 1 allowing the acting end of 70 the lever to have a full and free downward movement without interference from the base plate. Secured to the opposite end of the base plate 1 is a series of upright rods or bars 19, forming a guide for the extremity 75 of the longer or power arm of the lever 16. Supported upon these rods is an air cylinder 20, in which operates a piston 21, and which may be provided with any suitable construction and arrangement of supply and 80 exhaust ports, whereby the air from any suitable source of compressed air supply may be utilized. The piston 21 is provided with a depending stem 22 connected with a cross head plate 23 having guide grooves 85 receiving the rods on which it is fitted to slide. This cross head plate is coupled by a connecting rod 24 with the adjacent end c of the lever, whereby upon the downward movement of the piston 21 such end of the lever 90 will be depressed and the short end of the lever raised to move the compressor head 14 toward the head 8 for the purpose of compressing the material. It will be understood from the foregoing description that the 95 power of the air may be employed to simply operate the head 14 on its working movement, the weight of said head operating to return it, the lever, and the piston to normal position by gravity.

100 In operation, the material to be compressed is placed in the press chamber between the heads 8 and 14 and air admitted to the air cylinder to force the piston downward, whereby the head 14 will be moved upward for compressing action. It will, of course, be understood that the material may be compressed one or more times until it is compressed to the desired density, after which it is bound in any suitable manner 110 and the bale so formed removed.

115 By the construction described a very sim-

ple and inexpensive form of press is provided which may be operated at slight expense and which is particularly adapted for the use of small growers and others who desire to press cotton or other material into bales.

Having thus described the invention, what I claim as new is:

1. In a cotton press, the combination of a base having supporting portions at different elevations and an offset portion connecting the same, a compressor cylinder rising from the lower supporting portion, a compressor head working in said cylinder, an air cylinder mounted upon the higher supporting portion of the base, a piston operating in said cylinder, bracket members disposed upon the higher portion of the base adjacent to said piston, the latter being inclined at an angle therefrom to the lower supporting portion of the base and a walking beam or lever pivoted to said bracket members and in operative engagement at its opposite ends with the stems of the compressor head and piston head, said angularly disposed offset portion of the base permitting the power applying end of said lever to move down to a position in line with the base.

2. In a cotton press, the combination of a base having a depressed end provided with spaced arms, and formed adjacent said depressed end with upstanding lugs, cross plates extending between said spaced arms, a compressor chamber including rods or bolts having their lower ends passing through and coupled to said arms and cross plates and carrying at their upper ends a stationary compressor head, a guide bracket disposed in said chamber and having depending arms engaged by the bolts, and clamped between the arms and cross plates, a plunger stem movable in said guide bracket and carrying a compressor head, a lever pivoted to the lugs to provide long and short arms, said short arms being arranged to operate said plunger stem, an air cylinder mounted upon the opposite end of the base, a piston operated therein, and connections between said piston and the long arm of the lever.

In testimony whereof I affix my signature in presence of two witnesses.

MARSHALL M. MODE.
